MATERIAL HANDLING APPARATUS

Charles S. Johnson, Champaign, Ill.

Application June 9, 1937, Serial No. 147,172

5 Claims. (Cl. 212—81)

The invention relates to material handling apparatus and more particularly to such apparatus for hoisting and traversing quantities of such loose bulk materials as are, for example, used in building or road construction and the like.

The general object of the invention is to provide an improved form of material handling apparatus which is of such character that a single set of tackles may be readily used for different services such as moving and operating any one of a series of selectively available containers such as clamshell buckets, tank buckets, and the like, all without the necessity of unreeving the tackles or making other complicated and time-consuming adjustments.

A more specific object of the invention is to provide an improved form of demountable attachment head for detachably securing material handling buckets or containers to associated operating and hoisting tackles.

Another object of the invention is to provide in an apparatus of the type set forth a detachable connection between the container and associated tackles in which no removable pins or separate parts are used, thus obviating the possibility of their being misplaced or lost.

The invention also resides in the novel form of locking mechanism embodied in the demountable attachment head.

Further objects and advantages of the invention will become apparent as the following description proceeds and the features of novelty which characterize the invention are pointed out with particularity in the claims annexed to and forming a part of this specification.

For a better understanding of the invention, reference may be had to the accompanying drawings in which—

Figure 1 is an end elevation of a material handling apparatus embodying the invention.

Fig. 2 is a side elevation of the apparatus shown in Fig. 1 but with the trolley mechanism omitted and the bucket in open position.

Fig. 3 is an enlarged side elevation of the attachment head and associated tackle pulleys with a portion of the head broken away to illustrate its interior construction.

Fig. 4 is an enlarged detail sectional view along the line 4—4 in Fig. 3.

Fig. 5 is an exploded perspective view of the attachment head and its associated parts.

Fig. 6 is a detail plan view of the attachment head included in the apparatus shown in Figs. 1 and 2, certain of the parts being sectioned along the line 6—6 in Fig. 1.

Fig. 7 is a side elevation of the attachment head applied to a tank-type bucket for cement or the like.

For purposes of illustration and explanation of its various features, the invention has been shown herein as embodied in a material handling apparatus which may be used for conveying bulk construction materials of various types such, for example, as sand, gravel, and crushed rock. This apparatus includes as its principal elements a material container illustrated as a clamshell bucket 10, a lowering and hoisting tackle 11, a container operating and hoisting tackle 12, and a novel form of attachment head 14 for detachably connecting the bucket 10 to the associated tackle 15 rigging.

The clamshell bucket 10 is of conventional form and includes a pair of scoop-shaped shells 15 pivotally connected by a shaft 16 passing through a counterweight and pivot casting 17. The outer ends of the shells 15 are supported for opening and closing movement by rigid arms 18 pivoted at their lower ends on the outer portions of the shells as indicated at 19 and at their upper ends on the attachment head 14 as indicated at 20. It will be understood that a digging-type tackle-operated clamshell bucket or other form of material grasping container may be utilized if desired.

The associated cable rigging for the bucket 10 has been illustrated as of the well known "four-line" type although other cable arrangements such as a "two-line" type may be substituted if desired. In the rigging illustrated, the bucket 10 may be held or lowered in open position by the tackle 11 including a hoist-and-lower-open cable 21, as well as closed and hoisted in closed position by the tackle 12 including a close-and-hoist-closed cable 22. These cables 21 and 22 extend downwardly from suitable pulleys 23 on a trolley 24, which may be mounted for traversing movement on a horizontal I-beam track 25. One end 21a of the cable 21 is anchored while the other end passes over a suitable power actuated cable drum (not shown), the bight of the cable being reeved through a block or pulley 26 fast on the head 14. Similarly, one end 22a of the cable 22 is anchored while the other end passes over a second power actuated cable drum (not shown) and the bight of this cable is reeved through blocks or pulleys 27 and 28 fast respectively on the head 14 and bucket 10. It will be noted that the lower pulley 28 is detachably secured to the bucket casting 17 by a demountable connection designated generally by the numeral 29.

In lowering the bucket 10 in open position, the cable 22 is slacked off to permit the bucket shells to open by gravitational downward movement of the heavy pivot casting or counterweight 17 and the bucket is then lowered by unreeing the cable 21. Having been thus lowered in open position on the top of a pile of material, the bucket is caused to close and scoop up a load of the material by reeling in the cable 22, thereby raising the block 28 until it approaches the associated upper block 27 whereupon further reeling in of the cable 22 will cause the loaded bucket to be hoisted. The trolley 24 and its associated mechanism may be traversed along the track 25 by suitable traversing cables 30 and 31 or otherwise moved or handled as desired. The operation so far described is that had with ordinary four-line clamshell buckets and consequently, it is not believed to require further detail.

20 In order to facilitate ready detachment of the bucket 10 from the associated tackle rigging, the head 14 is constructed in two separable head-sections 32 and 33 which are demountable and may be detachably locked together as a unitary structure. All of the tackle connections to the head are made to one head-section and all of the container connections to the head are made to the other head-section. It will thus be seen that in general the tackle rigging may be disconnected 30 as a unit from the bucket by simply detaching the two head-sections 32 and 33 and connection 29, thus obviating the necessity of unreeving the tackles.

In the preferred construction illustrated, the head-section 32 is generally cylindrical in shape 35 while the associated head-section 33 is annular and fits about the first section in telescoping relation. Each of the head-sections is preferably made in the form of a heavy metal casting. An upper end wall 34 of the cylindrical head-section 32 forms a support to which the pulley or block 26 is rigidly secured (Figs. 3 and 6). This end wall 34 also supports a pair of roller-type guides 35 for the cable 22. In addition, the head-section 45 32 constitutes a protective housing and support for the upper pulley 27 of the container operating tackle, this pulley being journaled within the hollow head-section on a shaft 36. The annular outer head-section 33 is provided with a central opening 37 of ample diameter to permit the pulley 28 to pass freely therethrough when the head-sections are disconnected. A pivotal support for the upper ends of the bucket arms 18 is formed by laterally projecting trunnions 20 positioned on the sides of this head-section 33.

A rugged, strong, and easily manipulable connection between the head-sections 32 and 33 is formed by suitable interfitting projections thereon which are adapted to be moved into and out 60 of engagement by a relative rotational movement of the head-sections (Fig. 3). Thus, heavy up-standing bifurcated lugs or projections 38 are formed on the annular head-section 33 at diametrically opposed points thereon, these projections 65 presenting grooves or notches 39 on their inner faces which are adapted to receive complementary projections on the inner head-section 32. These latter projections on the head-section 32 are illustrated in the form of lugs 40 on an annular integral collar 41 extending about the lower 70 end of the inner head-section. Upon reference to Fig. 5, it will be seen that the axial width of the collar 41 is increased at the points at which the lugs 40 are formed so that the latter fit snugly 75 within the grooves 39 when aligned therewith. On

the other hand, when the head-sections 32 and 33 are rotated with respect to each other through an angle of, say, ninety degrees, the lugs 40 are moved out of engagement with the grooves 38 so that the head-sections may be moved out of engagement (Fig. 5). Undue strain on the interfitting lugs 38-40 when the bucket 10 is hoisted in loaded condition is obviated by the direct connection between the head-section 32 and pulley 27. Thus, the strain on the tackle 12 does not have 10 to be borne by the lugs 38-40 but is transmitted directly to the upper head-section 32 rather than through the lower head-section 33 to the upper head-section.

Locking of the head-sections in assembled relation to prevent a disengaging movement thereof is effected by a pair of manually operable bell crank levers 42 pivoted on laterally projecting ears 43 on the head-section 32. When in their lowered position (Fig. 3), the lower ends 43 of 15 these bell crank levers 42 enter slots 38a in the lugs 38 preventing rotation of the lower head-section 33 with respect to the head-section 32.

The demountable connection 29 between the tackle pulley 28 and bucket counterweight 17 20 25 includes a plurality of interfitting projections which may be releasably locked in engaged position. Thus, upon reference to Figs. 3 and 4, it will be seen that a pair of laterally extending segmental shaped ears 44 on bracket 45 of pulley 30 28 fit within a complementary annular recess 46 in the top of the casting 17. Segmental projections 47 on the casting 17 overlie a portion of the top of the recess 46 so that when the ears 44 35 are disposed beneath these projections (as shown in Fig. 4), the parts are locked in engagement, but they may be readily separated upon rotating the ears 44 into registry with the openings between the projections 47. A spring pressed latch 48 carried by the pulley bracket 45 enters a registering hole in the casting 17 when the ears 44 40 and projections 47 are in engagement thereby releasably preventing relative rotation between the interlocking parts.

In the construction illustrated, the separable 45 elements of the attachment head 14, as well as of the demountable pulley connection 29 are releasably secured together by devices which include only cooperating parts which are permanently secured to their respective associated elements. Thus, no separate slip-pins, bolts, or the like are included. Such an arrangement in which none of the attachment parts can be isolated from the main elements is particularly advantageous as it prevents vexatious delays due 50 to losing or misplacing such parts.

In the operation of the apparatus described above, if it is desired to detach the clamshell bucket 10, in order to substitute another type of container or for any other reason, this operation 60 may be quickly and easily performed without the necessity of changing the reeving of the associated tackle rigging. Thus, the pulley 28 is detached from the bucket, and the head-sections 32 and 33 are disengaged. Detachment of the pulley 28 is effected by releasing the latch 48 and then rotating the pulley 28 relative to the bucket through an arc of approximately ninety degrees 65 to disengage the ears 44 from the projections 47. The operator may then disconnect the head-sections by grasping the bell crank levers 42 and swinging them upwardly to disengage their lower ends from the bifurcated lugs 38 and subsequently twisting the head-section 32 by means of the lever handles to rotate the lugs 40 out of engage- 70 75 75

ment with the grooves 39. The detaching operation is thus quickly and easily performed without material alterations in the arrangement of the associated apparatus and at the same time, the construction is such as to preclude accidental disengagement of the parts in the course of operation. Moreover, as was previously noted, the possibility of loss of any of the attachment parts is also precluded.

10 In the event that it is desired to utilize a different container of the same or a different type, it may be readily attached to the same tackle mechanism. For example, it may be desired to utilize the tackle mechanism for purely hoisting purposes as distinguished from operating a material grasping container such as that described above. Thus, in Fig. 7, a cylindrical metal bucket 49 has been illustrated such as is used for conveying quantities of cement and the like. This bucket 20 is provided with an attachment head-section 33^a which is substantially identical in construction with the head-section 33 described above except that it is provided with laterally extending arms 50 rather than trunnions 20. The bucket 49 is supported from these arms 50 by suitable flexible cables 51. It will be seen that the head-section 32 may be inserted within the head-section 33^a and then rotated and locked in position therein by the bell crank levers 42 as heretofore described.

30 When using a container such as the bucket 49, the block 28 is hoisted to the elevated position indicated in Fig. 6 where it will not interfere with the bucket. It will be understood that a large variety of other types of containers may be utilized, these containers being provided with suitable attachment head-sections for cooperation with the head-section 32.

Although a particular embodiment of the invention has been shown and described in some detail for purposes of illustration, there is no intention to thereby limit the invention to such embodiment but, on the other hand, the appended claims are intended to cover all modifications within the spirit and scope of the invention.

45 I claim as my invention:

1. In a material handling system, a demountable material container attachment head comprising, generally annular head-sections arranged in telescoping relation, and means including an annular integral collar on one of said head-sections having laterally extending portions adapted to be moved into and out of complementary grooves disposed at spaced points on the other of said head-sections upon relative rotation thereof for

detachably maintaining said head-sections in assembled relation as a unitary structure.

2. In a material handling system, a demountable material container attachment head comprising, generally annular head-sections arranged in telescoping relation, and means including projections on one of said head-sections adapted to be moved into and out of complementary grooves on the other of said head-sections upon relative rotation thereof for detachably maintaining said head-sections in assembled relation as a unitary structure.

3. In a material handling system, a demountable material container attachment head comprising, generally annular head-sections arranged in telescoping relation, means including projections on one of said head-sections adapted to be moved into and out of complementary grooves formed in bifurcated spaced projections on the other of said head-sections upon relative rotation thereof for detachably maintaining said head-sections in assembled relation as a unitary structure, and means including levers pivoted on said head-section movable into and out of the openings in said bifurcated projections for locking said head-sections against relative rotation, said levers being provided with manual operating handles operable to move the same into and out of locking position and to rotate said one head-section.

4. In a material handling apparatus, a clamshell bucket including a pair of shells pivotally connected to a central counterweight, an associated operating tackle including a vertically movable pulley, means including interfitting projections on said counterweight and pulley for detachably connecting the same in operative relation, and means for releasably locking said projections against disengagement.

5. In a material handling apparatus, a clamshell bucket including a pair of shells pivotally connected to a central counterweight, as associated operating tackle including a vertically movable pulley, means including interfitting projections on said counterweight and pulley movable rotatively into and out of engagement for detachably connecting the same in operative relation, means for releasably locking said projections against inadvertent relative rotation, an attachment head having an aperture therein accommodating said pulley for vertical movement therethrough and means for operatively connecting said shell and said head.

CHARLES S. JOHNSON.
